COMBINED RECEPTACLE AND BRUSH
HOLDER

Alvin J. Millavec, Cleveland, Ohio

Application October 24, 1935, Serial No. 46,556

1 Claim. (Cl. 206—1)

This invention relates to receptacles or containers of a nature suitable for the packing of an assembled paste box and brush or like implement so arranged for shipment and sale, and which on being opened for use presents a suitable holder for the paste box while the brush is in use and a suitable container for the brush when not in use.

An object of the invention is to provide an efficient and simple construction having a minimum number of parts. Further objects are to afford convenience in use and to effect preservation of the paste or material. A still further object of the invention is to provide for an arrangement of parts whereby the paste or material containers may be repeatedly replaced; that is, for example, when the shoe polish is exhausted, a new container of shoe polish only is placed in the holder and assembled device ready for use by merely removing its individual cover, which may be disposed of, the cover for the composite container serving the purpose of the paste box cover thereafter.

The invention is particularly useful for such merchandise as shoe polish, a suitable brush or like applying device arranged in the self-contained unit fulfilling the above objects and having the characteristics and advantages which will become apparent from the following description.

30 In the drawings,

Fig. 1 is a vertical central section through the assembled brush and container.

Fig. 2 is a section taken on a plane indicated by the line 2—2 of Fig. 1.

35 Fig. 3 is a top plan of the main body container with the other parts removed.

Fig. 4 is a composite view showing the parts of the container and brush holder ready for assembly and use.

40 Fig. 5 is an enlarged sectional detail of the upper portion of the assembled units.

Fig. 6 is a view of the material container itself.

Referring particularly to Fig. 1, a main container designated 10 is shown as having a pressed or rolled thread portion at its normally lower end, as indicated at 11, with which threads co-operates a threaded flange 12 of a bottom or base cover 15. This cover is thus removable and is shown as carrying suitably affixed thereto a brush member having an element 16 secured as by a screw 17 to the central portion of the base member 15 while its bristles, indicated at 20, project upwardly, extending when not in use normally within the container as shown.

45 50 55 Into the top of the body 10 is removably fitted

the material container 22. For convenience this container will be referred to as the shoe polish container, although it is to be understood that such a container may be used in this combination for any and various kinds of material.

5 The upper portion of the container 10 is shown as turned inwardly, providing a flange 30 which in turn has a downwardly turned edge 31. Below the flange 30 are preferably formed rolled threads, indicated at 34, to which are fitted 10 similar threads 35 formed on the flange or skirt of a top cap or cover 36. Normally, this cover 36 may fit against and close the top of the comparatively flat or shallow container 22.

The material or shoe polish container is shown 15 as provided with an annular rib 24 which may normally rest upon the top of the flange 30 and this is shown as formed in the side wall of the shallow container, the top edge of this wall as just indicated meeting the underside of the cover 20 36 when in the closed and assembled position shown in Figs. 1 and 5.

For convenience in holding the polish container 22 in the container 10, the side walls of the container 22 are shown as pressed outwardly forming 25 vertically extending ribs or bosses 26. These pass through slots shown particularly at 38 in the top flange 30 of the container 10, and thereafter the container is given a partial turn, for example, a quarter turn, bringing these bosses to a position 30 removed from the slots 38 so that inadvertent removal is thereafter prevented while intentional removal is accomplished by merely bringing the bosses back into registration with the notches or slots 38.

35 The material such as the shoe polish may be normally packed in the flat containers 22 with a cover 28 fitted thereon. Assuming that such a container is filled with material, its cover 28 is removed and may be disposed of as no longer useful, the container having been previously fitted into the top flange of the larger container member 10 as described, after which the cover member 36 may be placed upon the member 10 and tightly closed by the threads 34 and 35, and the brush carrying base cover member 15 may be secured by the thread members 11 and 12 as described. The parts so assembled may be set aside for later use, excessive evaporation or drying of the brush being prevented by reason of its being 50 enclosed, and drying of the shoe polish or other material being avoided by its being tightly enclosed.

For use, the cover 36 is removed and the container 10 merely set on its bottom edge, presenting 55

the shoe polish upwardly. The bottom cover and brush member may be conveniently taken in the hand and applied to the polish material in the container 22 and thence to the surface to which it is to be transferred and applied. After use, the parts are reassembled as shown in Fig. 1. Upon exhaustion of the supply of shoe polish or other material, another filled container 22 may be substituted for the empty one, as described.

Having thus described my invention, what I claim is:

In combination with a cylindrical material container having an opening and being provided with a plurality of vertically extending ribs and

an annular rib, each projecting from the outer periphery of said container, of a cylindrical supporting member having a threaded end with the extreme end being inturned to form a supporting means by cooperating with the annular rib of said container, the supporting member having cooperating portions with said vertical ribs for positioning the container and preventing inadvertent removal of the container from the support, and a cover having a threaded end engageable with the threaded end of the support for closing the opening of the container and placing the assembly in tight engagement.

ALVIN J. MILLAVEC.
